(57) **CLAIM**

The ornamental design for a circular stapler, as shown and
described.

DESCRIPTION

FIG. 1 is a perspective view of the circular stapler
FIG. 2 is a top plan view of the circular stapler
FIG. 3 is a right side view of the circular stapler
FIG. 4 is a bottom plan view of the circular stapler
FIG. 5 is a left side view of the circular stapler
FIG. 6 is a front end view of the circular stapler
FIG. 7 is a rear end view of the circular stapler
FIG. 8 is a perspective view of the circular stapler with the tray
removed
FIG. 9 is a perspective view of a second embodiment of the
circular stapler
FIG. 10 is a top plan view of the circular stapler
FIG. 11 is a right side view of the circular stapler
FIG. 12 is a bottom plan view of the circular stapler
FIG. 13 is a left side view of the circular stapler
FIG. 14 is a front end view of the circular stapler
FIG. 15 is a rear end view of the circular stapler
FIG. 16 is a perspective view of the circular stapler with the tray
removed
FIG. 17 is a perspective view of a third embodiment of the
circular stapler
FIG. 18 is a top plan view of the circular stapler
FIG. 19 is a right side view of the circular stapler
FIG. 20 is a bottom plan view of the circular stapler
FIG. 21 is a left side view of the circular stapler
FIG. 22 is a front end view of the circular stapler
FIG. 23 is a rear end view of the circular stapler
FIG. 24 is a perspective view of the circular stapler with the tray
removed
FIG. 25 is a perspective view of a fourth embodiment of the
circular stapler
FIG. 26 is a top plan view of the circular stapler
FIG. 27 is a right side view of the circular stapler
FIG. 28 is a bottom plan view of the circular stapler
FIG. 29 is a left side view of the circular stapler
FIG. 30 is a front end view of the circular stapler
FIG. 31 is a rear end view of the circular stapler; and,
FIG. 32 is a perspective view of a circular stapler with the tray
removed.
The broken lines in FIGS. 6-7, 14-15, 22-23, and 30-31 are
included for the purpose of illustrating portions of the circular
stapler that form no part of the claimed design.
